UNITED STATES PATENT OFFICE.

L. M. SEVERANCE, OF DIXON, ILLINOIS.

IMPROVEMENT IN PLATFORM-SCALES.

Specification forming part of Letters Patent No. 36,918, dated November 11, 1852.

To all whom it may concern:

Be it known that I, LYMAN M. SEVERANCE, of Dixon, in the county of Lee and State of Illinois, have invented a new and useful Improvement in Platform-Scales; and I do hereby declare that the following is a full, clear, and exact description of the same, reference being had to the accompanying drawings, making a part of this specification, in which—

Figure 1 is a vertical section of my invention, taken in the line $x x$, Fig. 2; Fig. 2, a horizontal section of the same, taken in the line $y y$, Fig. 1. Figs. 3 and 4 are vertical sections of portions of the same, taken, respectively, in the lines $z z$ $x' x'$, Fig. 2; Fig. 5, a vertical section of a portion of the same, taken in the line $y' y'$, Fig. 2.

Similar letters of reference indicate corresponding parts in the several figures.

The object of this invention is to obtain a platform-scale which will be extremely simple in construction and capable of being manufactured at a comparatively small expense, not liable to get deranged by use, be compact and portable.

To enable those skilled in the art to fully understand and construct my invention, I will proceed to describe it.

A represents a rectangular box, constructed of stout plank or timber secured together in any proper manner. Within this box A there are placed two parallel bars, B B, which are connected by cross-pieces C C, the upper surfaces of which are flush with the upper surfaces of the bars B B, and the upper surfaces of the cross-pieces C C and the portions of the bars B B which are between them extend a trifle above the upper edge of the box A, and have a platform, D, secured to them, as shown in Fig. 1.

The bars B B, as well as the cross-pieces C C, are of wood, and the bars B are secured at their ends by staples a to links or clevises $b b'$, as shown clearly in Figs. 3 and 4. These links or clevises $b b'$ are suspended from knife-edged bearings c , attached to the opposite sides of levers D D' D' D'', the clevis b being attached to the levers D' D', and the clevis b' attached to the levers D'' D''.

The levers D' D' D'' D'' are constructed of wood, and are strengthened each by a metal bar, E, which is bolted or otherwise secured to

them. These bars E are bent upward at their inner ends, as shown at d , so as to be parallel with the inner ends of the levers and at a little distance from them.

The upper ends of the parts $d d$ of the bars E of the levers D' D' are connected by a link, F, which is connected to the lower end of a vertical rod, G, and the lower ends of the vertical parts $d d$ of the bars E are connected by a link, H, to which one end of a lever, I, is suspended by a link, d' .

The levers D' D' are suspended each by a clevis, e, from the upper part of the box A, said clevises being secured to the box by staples f and fitted on knife-edged bearings g , attached to the levers.

The bearings $c g$ of the levers D' D' D'' D'' pass through metal plates h , secured to the sides of the levers, and the bars E may be of steel and hardened at their parts $d d$ in order to prevent wear. The bearings $c g$ may be of steel and hardened, and also the clevises and links previously described.

The lever I has a longitudinal position in the box A, its fulcrum-pin i being in a clevis, J, which is connected to a cross bar, the bottom of the box A. The lever I, the end opposite to that which is connected to the levers D' D' is connected to the levers D'' D'', which are constructed like the levers D', the former being connected at their inner ends by a link, j , to which the lever I is suspended by another link, j' . The levers D'' D'', however, have their metal bars E secured to their upper surfaces instead of to their under surfaces, and the bars B B are attached to the levers D' D' at points between the clevises $e e'$, by which the levers D' are suspended from the upper part or top of the box A and the inner ends of said levers, while the opposite ends of the bars B are attached to the levers D'' at points at the outer side of the clevises e' , by which and staples e'' said levers D'' are suspended from the upper part or top of the box A. This arrangement in the mode of connecting the bars B B to the levers D' D' D'' D'' gives a vibratory movement to the lever I—that is to say, one end of said lever moves upward while the other end moves downward—when a weight is placed on the platform D.

The lever I is provided with metal bars or

straps i^x i^y , to which the links which connect the lever I to the levers D D' are attached.

The rod G is connected at its upper end to a beam, L, which is constructed of wood and has a metal bar, l, fitted in it. This beam L is provided with a graduated scale, l, and is suspended from a suitable fixture, m, by a rod, n, as shown in Fig. 1.

The operation of the beam L is the same as that of ordinary scales, and by the arrangement of the bars and levers as shown and described a very simple and compact platform-scale is obtained, one requiring no pit to receive the working parts. The scale also by my improvement may be constructed at a very reasonable cost. There are no parts liable to get out of repair or become deranged by use.

By constructing the bars B B of wood and

the levers D' D', D'' D'', and I of wood and metal combined a very light device is obtained, combined with strength, as hard wood possesses more strength than iron in proportion to its weight, and said parts cannot be bent, a contingency which would be liable to occur if constructed wholly of metal, and which would render the scale inaccurate.

Having thus described my invention, what I claim as new, and desire to secure by Letters Patent, is—

The combination of the parallel beams B B and levers D' D', D'' D'', and I, and the scale-beam L, all arranged as herein set forth.

L. M. SEVERANCE.
